CLAIM

The ornamental design for a eyeglass flotation retainer, as shown and described.

DESCRIPTION

FIG. 1 is a perspective view of an eyeglass flotation retainer showing our new design;

FIG. 2 is a first side view thereof with the second side view being a mirror image of the first side view;

FIG. 3 is a partial top plan view thereof, the bottom plan view being a mirror image of the top plan view;

FIG. 4 is a rear elevation view thereof; and,

FIG. 5 is a front elevation view thereof.

The broken line showing of the eyeglasses in FIG. 1 is for illustrative purposes only and forms no part of the claimed design.
